CLAIM

The ornamental design for a bladeless fan, as shown and described.

DESCRIPTION

FIG. 1 is a front, top, and side perspective view of a bladeless fan of the new design.

FIG. 2 is a back, bottom, and side perspective view thereof.

FIG. 3 is a front view thereof.

FIG. 4 is a back view thereof.

FIG. 5 is a left-side view thereof.

FIG. 6 is a right-side view thereof.

FIG. 7 is a top view thereof.

FIG. 8 is a bottom view thereof.

FIG. 9 is an enlarged view of a portion 9 shown in FIG. 1; and,

FIG. 10 is an enlarged view of a portion 10 shown in FIG. 7.

The dash-dash broken lines shown in the FIGURES illustrate portions of the bladeless fan that form no part of the claimed design. The dash-dot broken lines encircling portions of the bladeless fan in FIGS. 1, 7, 9, and 10 form no part of the claimed design.

1 Claim, 10 Drawing Sheets
